Charles G. Hensley.

UNITED STATES PATENT OFFICE.

BENJAMIN RABINOWITZ, OF BROOKLYN, NEW YORK, ASSIGNOR OF ONE-HALF TO
ISRAEL H. KAPLAN, OF BROOKLYN, NEW YORK.

LIGHTING SYSTEM FOR CARS.

Application filed November 3, 1921. Serial No. 512,471.

To all whom it may concern:

Be it known that I, BENJAMIN RABINOWITZ, a citizen of the United States, and a resident of the borough of Brooklyn, city 5 and State of New York, have invented certain new and useful Improvements in Lighting Systems for Cars, of which the following is a specification.

My invention relates to an automatic lighting system for cars or trains. The object is to provide, in connection with the lamps by which the car or cars are lighted, automatic means for throwing on the lights when the car or train is about to enter a 10 tunnel or to pass under a bridge or to enter any place where the car or cars might require temporary lighting; and to turn off the lights when the car or train emerges from such localities. Where a car is operated in the daytime and it occasionally enters a poorly lighted or dark section such as a tunnel, bridge, or other location, it is often necessary to turn on the lamps temporarily to avoid accidents to passengers in the car 15 and in many places the public ordinances or laws make it obligatory to turn on the lights temporarily. The conductor or trainman in such cases is required to give some attention to the operation of the lights. 20 Where the section requiring temporary lighting is passed through quickly the conductor or trainman is very likely to neglect to operate the lights and this may result in an accident occurring to some passenger owing to 25 lack of light in the car. The object of the present invention is to provide automatic means for switching on and off the lights where light is required only temporarily as when passing through tunnels, under bridges, 30 through viaducts, etc. Another object is to provide a corrective switch by means of which the circuit may be corrected in case the lamps are turned off when they should be turned on and vice versa. The circuit 35 may be corrected by simply throwing over a switch and thereafter the device will operate correctly. I also provide a shunt circuit in connection with the above to permit the lamps to be turned on for continuous lighting at night when the intermittent lighting 40 is not required.

The present device is intended as a protection and it is also intended to save in the 45 consumption of current because it is often the custom now to turn on the lights when

a car approaches a dark place and to leave the lights turned on for some time after the car emerges from the dark place and this causes a waste in current.

In the drawing forming part of this application,

Figure 1 is a diagrammatic view of my lighting system as applied to a car.

Figure 2 is a sectional view of a car truck showing the automatic switch mounted 65 thereon,

Figure 3 is a sectional view of the automatic switch,

Figure 4 is an end view thereof, and

Figures 5 and 6 are sectional views 70 thereof.

The present device may be applied to a car operated singly or to a number of cars in a train. In the latter case each car may have a separate and complete installation 75 or one set of switches may control all the lights for the whole train.

In Figure 1 I have shown diagrammatically my improved device. Herein, I have shown a number of lamps 1 which it is to 80 be understood are placed in one or more cars for lighting the interior thereof. These lamps are connected as to one pole with the wire 2 and as to the other pole with the wire 3; and the circuit includes a source of 85 current 4 which may be a battery or the service circuit from which the car is operated.

From one side of the source of current supply I have shown a wire 5 running to a pair of switch knives 6 and 7 with which the automatic switch 8 is associated. There is a wire 2, 9, running from one side of the lamps and this wire is adapted to be connected through a correcting switch 10 with 90 either the wire 11 or the wire 12. At the other end of the wire 11 I have arranged a switch knife 13; and at one end of the wire 12 I have arranged a switch knife 14. Through the automatic switch 8, the details 95 of which will be later described, the wire 11 or the wire 12 is adapted to be connected up with the wire 5.

I have provided a shunt circuit comprising a wire 15 connected with the wire 2 and a wire 16 connected with the wire 5 and the wires 15, 16, are adapted to be connected and disconnected by means of a switch 17.

The automatic switch is preferably mounted on the truck of the car and about in the 110

- transverse central line thereof in order that it may be operated by the same actuating devices in whichever direction the car travels on the track. In Figure 2 I have indicated a car body 18 mounted on the truck 19, the wheels of which travel on the track rails 20. The automatic switch 8 is shown mounted on the truck bolster 21 where the revolvable spoke wheel 22 may be turned a quarter turn each time it engages with one of the actuating devices 23 which I have shown attached to one of the railroad ties 24 and which member 24 may consist of a simple plate projecting above the ties.
- Any automatic switch may be employed for the purpose. The one shown herein by way of example is constructed as follows: There is a shaft 25 projecting from the casing 26 and it has a spoke wheel 22 which is operated on by one of the stationary plates 23 arranged near the path of the car. This wheel 22 is turned 90° each time it is actuated by one of the plates 23. On the shaft 25 there are arranged the straps 27 for engaging any of the free ends of the several switch knives 6, 7, 13, 14; and opposite the straps 27 there is another pair of straps 28 which are also adapted to engage any of the switch knives. There is a disk 29 fixed to the shaft 25 and one end of a coiled spring 30 which surrounds the shaft 25, is connected with the disk 29 and its opposite end is fixed to a disk 31. The straps 27, 28, and the disk 31 are connected together to move as one and they are loose on the shaft 25. The disk 31 has a radial slot 32 and the disk 33, lying adjacent thereto, has a lateral projection 34 which engages in the slot 32. The disk 33 is loose on the shaft 25 and it has a shoulder 35 on its peripheral edge which engages with one or the other of the later projections 36 on the casing, which projections 36, are arranged 90° apart around a circle. When the spoke wheel 22 is turned a quarter turn it turns the shaft 25 and the disk 29 puts a torsional strain on the spring 30. The latter is contracted by this action and the disk 33 may slide along the shaft 25 enough to allow the shoulder 35 of the disk 33 to pass the abutment 36 with which it engages. When the disk 33 escapes one of the projections 36 the shaft 25 and the straps 27, 28, rapidly revolve 90° and then the shoulder 35 engages the next projection 36 and the rotation of the shaft and of the straps is arrested until the spoke wheel 22 is again turned.
- Operation: Assuming the switch 17 is open and the switch 10 is in the full line position shown in Figure 1. Let it be assumed that the car starts on its trip with the straps 27, 28, connected to the knives 6 and 14 and under this condition the lamps will be out because the wire 5 will be connected with the wire 12 and the circuit will be open at the switch 10 and the wires 11 and 5 will be disconnected at the automatic switch. When the car approaches a tunnel or other section where it is necessary or desirable to have the lights turned on, one of the plates 23 arranged to engage the spoke wheel 22 just before the car enters the tunnel, will turn the spoke wheel one quarter revolution and this will turn the straps 27, 28 a quarter turn. One of these straps will then connect with the knife 7 and the other will connect with the knife 13 and this will effect the following changes in the circuit. The change of position of the straps will disconnect the wire 12 from the wire 5 and 80 it will connect the wire 5 with the wire 11. The circuit will then be closed through the wire 5, the wire 11, the switch 10 and wires 9, 2, to the lamps 1 and from the lamps through the wire 3 back to the source of current. Thus, the lamps will be lighted. When the car emerges from the tunnel or other dark section it will meet with another plate 23 and the latter will again rotate the spoke wheel 22 a quarter turn. This will 85 bring the straps 27, 28 into connection with the knives 6 and 14. The wire 5 will then be connected with the wire 12 and the circuit will be broken at the switch 10 and the lamps will be extinguished. These operations will be repeated each time the car passes into and leaves a dark section, or wherever the plates 23 are arranged.
- If at any time the automatic switch should be out of time with operating conditions, so 100 that the lamps are extinguished when the car enters a tunnel and are lighted when it emerges therefrom, the conductor or trainman merely has to reverse the switch 10 to correct the error. By throwing over the 105 switch 10 to the dotted line position in Figure 1, the wire 11, will be disconnected from wire 9 and the wire 12 will be connected to the wire 9 and if the lamps were previously lighted they will be extinguished and 110 vice versa. The automatic switch will go on operating as before but the lights will be lighted when wire 5 is connected with the wire 12 through the switch 8 and at other times the lights will be extinguished. 115 Any subsequent time that the lamps are out of time with operating conditions the correcting switch 10 is simply thrown back and this reverses the automatic switch connections.
- At night the switch 17 is closed and then the lamps remain lighted continually, the circuit being then completed through the shunt wires 15, 16. The operation of the automatic switch will then not affect the 120 lamps. When daylight commences the switch 17 is opened and the automatic device operates as above described.
- From the above it will be apparent that 125 by arranging the plates 23 at suitable loca-

tions along the course of the car the lamps may be automatically lighted and extinguished for temporarily lighting the car at certain desired locations.

5 Having described my invention what I claim is:—

1. A lighting system for cars comprising lamps arranged to light a car and connected with a source of electric current, a switch 10 associated with the car and adapted to turn said lamps on and off, means arranged near the path of travel of the car and adapted to operate said switch for the purpose of automatically turning on and off said lamps, and 15 a correcting switch for reversing the operation of said automatic switch on said lamps.
2. A lighting system for cars comprising lamps arranged to light a car and connected with a source of electric current, wires connected with the opposite poles of said lamps, 20 a plurality of wires adapted to be connected with said first wires, an automatic switch associated with the car and means arranged near the path of travel of said car for operating said switch, said automatic switch 25

being adapted to alternately connect the wire from one pole of said lamps with said plurality of wires, and a correcting switch adapted to connect either of said plurality of wires with the wire which is connected 30 with the other pole of said lamps.

3. A lighting system for cars, comprising lamps arranged to light a car and means for connecting said lamps with a source of current, a wire connected with one pole of said 35 lamps, a plurality of wires either of which is adapted to be connected with said first wire, an automatic switch associated with the car and including a revolving member, and means arranged near the path of travel 40 of the car for operating said revolving member, said automatic switch being adapted to successively connect and disconnect said plurality of wires with said first wire, a wire connected with another pole of said lamps, 45 and a switch adapted to connect said latter wire with either of said plurality of wires.

Signed at the city, county and State of New York, this 19th day of October, 1921.

BENJAMIN RABINOWITZ.
